J. T. KING

2,466,953

FASTENER

Filed Dec. 29, 1948

James T. King,

Albert E. Dieterich,

ATTORNEY

UNITED STATES PATENT OFFICE

2,466,953

FASTENER

James T. King, Eagle Rock, Calif.

Original application September 8, 1947, Serial No. 772,845. Divided and this application December 29, 1948, Serial No. 67,865

3 Claims. (Cl. 85—1)

1

My invention relates to devices for securing two or more parts together under tension, and it particularly has for its objects:

1. To provide a fastener which can be used to hold two or more flat articles together.
2. To provide such a fastener as can be tightened from time to time so as always to ensure a good and reliable means to hold two parts together, which parts due to shrinkage tend to loosen up.
3. To provide a fastener whose parts can be made of sheet metal and by a punch press process.
4. To provide a fastener which can be installed or removed in difficult or confined spaces.

Other objects will in part be obvious and in part will appear later.

To the attainment of the aforesaid objects and ends, invention resides in the novel features of construction, combination, and arrangement of parts, all of which will first be fully described and then be specifically pointed out in the appended claims, reference being had to the accompanying drawings, in which:

Fig. 1 is a view partly in section showing one application of my invention.

Fig. 2 is a detail plan view looking in the direction of the arrow in Fig. 1.

Fig. 3 is a section on the line 3—3 of Fig. 4.

Fig. 4 is an elevation of the retainer used in the embodiment of my invention shown in Figs. 1 et seq.

Fig. 5 is an inverted plan view of the retainer.

Fig. 6 is a front elevation of the T-bolt used in the same.

Fig. 7 is a plan view of the retainer blank before bending to shape.

Fig. 8 is a plan view of the T-bolt before bending to shape and after the threads have been stamped thereon.

Fig. 9 is a view similar to Fig. 2, showing a modification later specifically referred to.

In the drawings in which like numerals of reference indicate like parts in all the figures, 1 represents a portion of the body of an automobile, 2 the fender and 24 the usual anti-friction strip and bead.

In using my invention to secure fenders to the body, the body and fender are drilled to provide holes 4 and 5. A retainer 6 is provided which is stamped from sheet metal (Fig. 7), slits 9, 10, 11 being made in the blank so that a stem 8 and a tab 7 are formed. The stem and tab are bent on the respective dot and dash lines 12, 13 in opposite directions, and the stem stamped to semi-cylindrical form (Fig. 5).

2

A T-bolt is formed from a blank (as shown in Figs. 6 and 8) by which is provided a head 14, a neck 15 and a threaded semi-cylindrical stem 16.

In use, the stem 16 is passed down through the aligned holes 4, the plate 6 is laid up against the under side of the fender with tab 7 projected up through the holes 5, and a nut 17 is placed over the stems and drawn up tight.

If the structure is such that the T-bolt cannot be passed through the holes 4 due to lack of space, then additional slots 5^a merging with the holes 4^a are provided and the T-bolt is passed up head-first and turned 90°, as indicated in Fig. 9. Tab 7^a then projects through the cross slots 5^a.

For new work the fenders may have the discs 6 welded thereto, or the stem 8 may be stamped directly from the fender itself.

Other changes will be apparent to those skilled in the art.

20 This application is a division of my application Serial No. 772,845, filed September 8, 1947.

From the foregoing description, taken in connection with the accompanying drawings, it is thought that the construction and advantages 25 of my invention will be clear to those skilled in the art to which it appertains.

What I claim is:

1. Means for securing two flat members together in parallel, said two members having a stem-passing hole; said means comprising a retainer for engaging one face of one of said two flat members and having a semi-cylindrical smooth stem, a T-bolt comprising a head for engaging the opposite face of the other of said two flat members and including a semi-cylindrical threaded stem complementary to the stem of the retainer and constructed to pass through said stem-passage, and a nut on and embracing said stems in threaded engagement with said threaded stem for drawing the retainer and the two flat members tightly together.

2. Means for securing two flat members together in parallel, said two members having a stem-passing hole; said means comprising a retainer for engaging one face of one of said two flat members and having a semi-cylindrical smooth stem, a T-bolt comprising a head for engaging the opposite face of the other of said two flat members and including a semi-cylindrical threaded stem complementary to the stem of the retainer and constructed to pass through said stem-passage, and a nut on and embracing said stems in threaded engagement with said threaded stem for drawing the retainer and the two flat members tightly together, said flat members hav-

ing a second hole and said retainer having a tongue to enter said second hole to prevent swivelling of said retainer and T-bolt on their combined axis.

3. Means for securing two flat members together in parallel, said two members having a stem-passing hole; said means comprising a retainer for engaging one face of one of said two flat members and having a semi-cylindrical smooth stem, a T-bolt comprising a head for engaging the opposite face of the other of said two flat members and including a semi-cylindrical threaded stem complementary to the stem of

10

the retainer and constructed to pass through said stem-passage, and a nut on and embracing said stems in threaded engagement with said threaded stem for drawing the retainer and the two flat members tightly together, said flat members having a slot cooperating with said stem-passing hole for passage of the head of said T-bolt, said retainer having a tongue to enter said slot when said head is cross-wise of the slot.
